CIGARETTE CASE

Leo J. Du Mais, Chicago, Ill.

Application July 28, 1941, Serial No. 404,355

4 Claims. (Cl. 206—41.2)

The present invention relates to a cigarette case, and is more particularly directed to a type of case from which cigarettes may be projected to be selectively gripped to be withdrawn from the case.

It is an object of the present invention to provide a small, sturdy, compact and inexpensive cigarette case, which is simple in construction, durable and easy in operation, and in which case, a full package of cigarettes may be inserted and retained in the manner packed in the package, and with means whereby they may be readily projected from the case to be individually removed.

Another object is the provision of a cigarette case having a cigarette tensioning means therein whereby the cigarettes are constantly urged in one direction to be projected in tiers, rendering them accessible to be selectively gripped to be removed from the case.

A further object is the provision of a cap means serving with a cover to tightly close the case, and which cap means is movable with the projected cigarettes when the projecting means is actuated, and said cap means serving to engage and force the return of the remaining cigarettes after one has been removed, and the projecting means is restored to its normal position.

And a further object is the provision of cigarette projecting means having the cap means arranged for movement therewith and with manually manipulative means operatively connected to the projector means for effecting the projecting movement of the projector means and the cap means.

And a still further object is the provision of lock means coacting to retain the cover in closed position on the case while permitting of free movement of the cap means, and which cover serves to retain the cigarettes other than those being projected within the case; the cover and cap means also provide means for opening one end of the case for bodily inserting the cigarettes as contained in the original package; the provision of shelf means on the projector means which extends through and is aligned with the bottom wall of the case for receiving cigarettes thereon, and the opening through which the shelf extends, serves to dispose of loose particles of tobacco which may be sifted from the cigarettes during their stay in the container.

Further objects and advantages will become apparent from the ensuing description and drawing, in which:

Figure 1 is a perspective view of the cigarette case embodying my invention.

Figure 2 is a perspective view of the cigarette case in open position, and with a package of cigarettes, shown in dot and dash lines, to be inserted therein, and with the lower portion of the case broken away to show the position of the parts when the case is open.

Figure 3 is a longitudinal sectional view taken substantially on the line 3—3 of Figure 1.

Figure 4 is a perspective view illustrating the position the projector means and cap means assume when a tier of cigarettes is projected from the case, and shows also the opening through which loose particles of tobacco are sifted.

Figure 5 is a detail perspective view of the projector means illustrating the cigarette-engaging shelf at the lower end thereof.

Figure 6 is a detail perspective view of the actuating means for the cigarette projector means.

Figure 7 is an enlarged detail fragmentary sectional view showing the spring means coacting between the projector means and cap means and exerting a pressure to throw the cap means to open position when the projector means is actuated to project the cigarettes.

Figure 8 is an enlarged detail fragmentary sectional view showing the spring means for the cigarette tensioning means, and also the spring means for urging the cover to open position.

The cigarette case is illustrated as of a size for receiving the standard size of cigarettes, or may be of a size for receiving the longer or "king" size which has recently been introduced on the market.

The cigarette case comprises a container 10, which as shown, is preferably formed of relatively thin sheet material which may be embellished to provide various designs, etc., and which will also serve to reinforce or strengthen the container. This container is shown as being substantially rectangular in shape, so as to closely resemble the size of a package of cigarettes, and has side walls 11 and 12 and end walls 13 and 14 and a bottom wall 15, and an open top end 16. The end wall 13 of the container is provided at near its top edge with a formed hinge 17 and with a relatively small opening 18 located a short distance below the hinge and centrally of the wall. The hinge 17 serves to pivotally support a U-shaped actuating member 19 which is also provided with hinge formation 20 at the top edge of its wall portion 21 to coact with the hinge portion 17 of the container 10 and provided with a hinge pin 17a to support the same. The wall portion 21 of the member 19 is also provided with a projecting finger member 22 which extends through the opening 18 in the end wall

13 when the U-shaped member 19 is in position in the container. Each of the legs 23-23 of the U-shaped member 19 is provided at its free end with pin-receiving portions 24-24, which receive a hinge pin 25 extending through hinge formations 26 of a slidable or projector member 27. This slidable or projector member 27 is provided at its lower end portion with an integral cigarette-receiving shelf 28 which extends through an opening 29 in the bottom wall 15 of the container, and is retained flush therewith under the tension of a spring 30 which has one end secured to the hinge pin 25 and its other end secured to an ear 31 fixed to the end wall 14.

The hinge pin 25 also serves to pivotally support a cap means 32 which is substantially L-shaped, providing a wall 32a which is formed to provide a shoulder 32b that normally rests on the edge 14a of the end wall 14, as viewed in Figs. 3 and 7, and the wall 32a of the cap means has its lower edge provided with a hinge formation 33 to be engaged by the hinge pin 25. The cap means 32 is also provided with outwardly directed ears 32c which engage the open top end 16 of the container 10, and these ears serve with the shoulder 32b to limit the restoring movement of the cap 25 and the projector member 27. A torsion spring 34, which has its body coiled around the hinge pin 25 and has one end 35 engaging the cap means 32 and its other end 36 engaging the slidable-projector member 27, serves to exert a constant outward pressure on the cap means 32 which keeps the back wall 32a thereof in sliding contact with the edge 14a of the end wall 14 of the container.

A relatively wide cigarette tensioning spring 37 is pivotally carried to swing in the container on the hinge pin 17a, and is of a length to extend to near the bottom wall 15 of the container, and when swung in its upward position, will engage formed stops 19a on the U-shaped member 19. This tensioning spring 37 is normally urged in upward position by means of a relatively light torsion spring which has its body 38 coiled on hinge pin 17a and one end 39 underlying the tension spring 37 and its other end 40 engaging end wall 13.

The hinge pin 17a also pivotally supports a cover 41 which is of relatively shallow formation having side walls 42-42 which are arranged to engage and rest upon the top edge of the side walls 11 and 12 of the container 10, and which cover is of a length to serve with the cap means 32 to close the opening 16 of the container. Each of the side walls 42 of the cover 41 are provided at their free end portions with downwardly projecting ears 43-43 arranged to closely hug the side walls 11 and 12 of the container and which ears are provided with openings 43a-43a which serve to receive outwardly projecting bevelled lugs 44-44 on the side walls 11 and 12 of the container.

A torsion spring 45 has its body coiled on hinge pin 17a and has one end 46 engaging the cover 41 and its other end 47 engaging the end wall 13. This spring 45 exerts an upward pressure on the cover which is normally locked in closed position by reason of the ears 43-43 engaging lugs 44-44.

When the case is to be opened for filling, the side walls 11 and 12 of the container are pressed to cause them to spring inwardly sufficiently to release the lugs 44-44 from ears 43-43, which renders the cover 41 free to be impled to open position by its spring 45. Then the wrapper A on the package of cigarettes B (dot and dash lines Fig. 2), is torn off to approximately the middle of

the package to expose the cigarettes. At this time, the finger member 22 is pressed which opens the cap means 32, and the exposed ends of the cigarettes are forced into the container against the tensioning spring 37 which rocks downwardly against the tension of its spring 38 and frictionally retains the cigarettes while the remaining portion of the wrapper A is removed. The cigarettes are then pressed into the container and the finger member 22 is released to close the cap means 32, and the cover 41 is then closed against the tension of its spring 45 and releasably retained in closed position by the ears 43-43 engaging lugs 44-44.

After the cigarettes are in the case, the tension spring 37 which is of very thin and flexible spring material, is constantly in engagement with the cigarettes by reason of the tension exerted thereon by spring 38. These springs 37 and 38 form the tensioning means for the cigarettes to urge them in one direction, and as the cigarettes are projected and removed, the remaining cigarettes will be bodily moved toward the projector means until they have all been projected and removed from the container. Due to the flexibility of the tension spring 37, it will yieldingly engage the cigarettes to exert an even pressure along their length without bending or marring them in any way while retaining them aligned in rows.

The projector means 27 is of a width to loosely fit with the container and to accommodate three cigarettes. In order to guide the cigarettes in upright position, the projector means is provided with longitudinally formed guides 27a that project inwardly, and as the cigarettes are forced by the tensioning means comprising springs 37 and 38 against the projector means 27 and over the shelf 28 thereof, the cigarettes will be guided by the guides 27a into the spaces 27b, 27c and 27d (Fig. 5).

After the cigarette case has been filled and it is desired to remove a cigarette, the finger member 22 is pressed inwardly, which effects an upward rocking movement of the U-shaped member 19 and carries the projector means 27 therewith and with three cigarettes which are normally in the spaces 27b, 27c and 27d, and which cigarettes are engaged by the shelf 28 of the projector means.

This upward movement of the U-shaped member 19 also carries the cap means 32 therewith and when it has reached the limit of its movement, the cap means will be bodily swung outwardly on hinge pin 25 by its spring 34 over the edge 14a of the end wall 14, which permits of easy access to the projected cigarettes. During this upward movement, the projected cigarettes slide longitudinally of the adjacent cigarettes which are withheld from movement therewith by the cover 41. As it will be noted in Fig. 3, the container is approximately an eighth of an inch longer than the cigarettes and will permit of a slight longitudinal shifting movement of the remaining cigarettes, due to their frictional engagement with those being projected. This shifting movement causes the cigarettes to align themselves with respect to each other and prevents packing.

The cap means 32 which is normally flush with the cover, is also approximately an eighth of an inch above the cigarettes, and after the cigarettes are projected and one of them is removed, this additional space permits of the swinging movement to vertical position of the cap means over the remaining projected cigarettes during its restoring movement when the finger member

22 is released, and the cap means then engages the top ends of the cigarettes and restores them within the container.

During this projecting and shifting movement of the cigarettes, the loose particles of tobacco sifted therefrom, will drop through the opening 29 in the bottom wall 15 of the container, thereby keeping the container relatively clean.

The ear 31 fixed to the end wall 14 also serves to guide the projector means 27 during its vertical sliding movements under the control of the U-shaped member 19, and the spring 30 which is fixed to ear 31 and to the hinge pin 25, is of sufficient tension to restore the cap means against the tension of its spring 34 when the U-shaped member 19 is released.

While the projected cigarettes are being selectively removed, the guides 21a will retain the remaining cigarettes in upright position and prevent their tilting movement from side to side, while the tensioning means yieldingly retains them against the projecting means.

While I have shown and described a preferred embodiment of my invention, and do not wish to be limited to the precise details of construction set forth, but desire to avail myself of all changes within the scope of the appended claims.

I claim:

1. A cigarette case comprising, an open end container through which cigarettes may be positioned in the container, a pivoted spring-urged cover partially closing the open end of said container and providing a reduced opening therein, means on said cover and container coacting to releasably lock the cover in closed position against its spring, a member having cigarette engaging means thereon, cap means pivoted on said member serving with said cover to close the container, manually manipulative means oper-

atively connected with the said member for effecting movement thereof with the cap means to project cigarettes through said reduced opening whereby they may be individually removed, and a spring normally restoring the said member and cap means with the manipulative means.

2. A cigarette case comprising, a container for cigarettes having a reduced opening therein through which the cigarettes may be projected, means for projecting the cigarettes outwardly of the container through said reduced opening, manually manipulative means for effecting the projecting movement of said projecting means including spring means normally restoring said projecting and manipulative means, means exerting a tension on the cigarettes urging them toward the said projecting means, and stop means on said manipulative means engageable by said tension means for limiting the movement of the tensioning means in one direction.

3. A cigarette case comprising, a container for cigarettes having a reduced opening through which the cigarettes are projected, cigarette projecting means, a cap means pivoted on said projector means for normally closing the said reduced opening and for opening the same when cigarettes are projected, said cap means serving to engage to restore the projected cigarettes when restored with said projecting means, a spring coacting with said projecting means for restoring the same and cap means, and means on said cap means engaging the container limiting its restoring movement with the projecting means.

4. The combination of claim 3 hereof in which there are guide means on the container for guiding said projecting means during its projecting and restoring movements.

LEO J. DU MAIS.
